(57) **CLAIM**

The ornamental design for a male straight urinary catheter, as shown and described.

DESCRIPTION

FIG. 1 is a perspective view of a male straight urinary catheter;

FIG. 2 is a front side view thereof;

FIG. 3 is a back side view thereof;

FIG. 4 a top side view thereof;

FIG. 5 is a bottom side view thereof;

FIG. 6 is a left side view thereof;

FIG. 7 is a right side view thereof; and,

FIG. 8 is a view of an enlarged portion of a handle of the male straight urinary catheter shown in FIG. 1.

The broken lines in the drawings illustrate portions of the male straight urinary catheter and form no part of the claimed design.

The dot-dash broken lines represent boundaries of the enlarged portion and form no part of the claimed design.
